UNITED STATES PATENT OFFICE.

HENRY O. PEABODY, OF BOSTON, MASSACHUSETTS.

DESIGN FOR A SHOULDER-REST FOR VIOLINS.

SPECIFICATION forming part of Design No. 26,220, dated October 27, 1896.

Application filed August 5, 1896. Serial No. 601,817. Term of patent 14 years.

To all whom it may concern:

Be it known that I, HENRY O. PEABODY, of Boston, in the county of Suffolk and State of Massachusetts, have invented and produced a new and original Design for a Shoulder Rest or Support for Violins, of which the following, taken in connection with the accompanying drawings, is a specification, reference being had to the accompanying drawings, showing a part thereof.

The leading feature of my design consists in a knob the main outer portion of which has formed thereon a series of annular beads of varying diameters, said beads all having their surfaces milled or roughened by a series of slight indentations extending transversely of said beads, said outer portion of said knob having a general outline resembling an inverted straw beehive, said main portion or head being surmounted by a smooth circular neck the outer surface of which is curved in the direction of the length of the axis of said knob, a smooth circular flange surmounting said neck, and a screw-threaded shank projecting from the center of said flanged end.

In the drawing, A is the main body or head

of the rest or support, having the series of peripheral beads $\alpha\alpha$ of constantly-varying diameters and each having its outer surface roughened by transverse creases or indentations, as shown. 30

The rest or support is also provided with the smooth circular neck b, having its outer surface curved in the direction of the length of the axis of said rest, and connects said head to the smooth circular flange c, which surmounts it, and is provided with the screw-threaded shank d, projecting from the center of said flanged end, as shown. 35

What I claim is—

The design for a shoulder rest or support for violins substantially as herein shown and described. 40

In testimony whereof I have signed my name to this specification, in the presence of 45 two subscribing witnesses, on this 4th day of August, A. D. 1896.

HENRY O. PEABODY.
